United States Patent

Des. 237,796
Patented Nov. 25, 1975

237,796

SPRAY GUN

Josef Wagner, Markdorferstr. 165, Friedrichshafen-Spallenstein, Germany

Filed Oct. 23, 1974, Ser. No. 517,041

Term of patent 14 years

Int. Cl. D23—01

U.S. Cl. D23—18

Fig. 2

FIG. 3

FIG. 4

FIG. 5

FIG. 1 is a perspective view of a spray gun showing my new design;

FIG. 2 is a top plan view thereof;

FIG. 3 is a side elevational view thereof;

FIG. 4 is a rear elevational view thereof; and

FIG. 5 is a bottom plan view thereof.

The electric cord has been broken away in FIGS. 2 through 5 for convenience of illustration.

I claim:

The ornamental design for a spray gun, as shown and described.
